UNITED STATES PATENT OFFICE.

EINAR MOLMARK, OF AMBRIDGE, PENNSYLVANIA.

ELECTRODE HOLDER.

Application filed March 19, 1928. Serial No. 262,941.

This invention relates to electrode holders, and more particularly to holders for large electrodes such as used in electric metallurgical furnaces, retorts and the like, and has for its object the provision of an electrode holder that will clamp or hold the electrode securely and will automatically compensate for the expansion caused by the heat.

Heretofore, electrode holders of the class to which this invention belongs have generally been of a split formation and clamped around the electrode, and have been water-cooled to prevent excessive expansion, which would allow the electrode to drop.

The electrode holder of this invention eliminates the use of water cooling, the body portion is formed integral or continuous, and the electrode may be clamped or released by the operation of a single lever.

In the drawings:

Figure 1 is a side elevation of an electrode holder constructed in accordance with my invention.

Figure 2 is a top plan thereof.

Figure 3 is a side elevation, partly in section, showing a slightly modified form of electrode holder.

Figure 4 is a top plan thereof.

Figure 5 is a side elevation, partly in section, showing a still further modified form of electrode holder.

Figure 6 is a top plan thereof.

Referring more particularly to the drawings, the numeral 2 designates the continuous ring-like body of the electrode holder as a whole, which has a projecting portion 3 on one side for connecting to the furnace and to the bus bar (not shown) and a second slotted projection 4 on the side opposite the projection 3 for a purpose to be described.

The inside wall of the body 2 is recessed at a point opposite the projection 3 to receive a wedge-shaped clamping shoe 5. The rear face 6 of the recess is inclined so as to cooperate with the wedge-shaped shoe when said shoe is moved vertically to force said shoe inwardly.

The inner face of the shoe 5 is formed concave or curved to fit the curvature of the electrode. The upper end of the shoe 5 is provided with an upwardly extending lug 6 which is apertured horizontally to receive a pivot pin 7. A toggle link 8 is pivotally connected to the lug 6 by the pin 7 and has its other end pivotally connected by a pin 9 to

the lower end of the short arm of a crank lever 10 which is pivotally mounted on a pivot pin 12 journaled in bearings 13 on the upper end of the projection 4. A counter-weight 14 is adjustably mounted on the long arm of the crank lever 10 and is adapted to apply a constant force to the lever 10 so as to extend the toggle composed of the short arm of the lever 10 and the link 8 so as to move the shoe 5 against the electrode.

A link 15 has one end pivotally secured to the long arm of the lever 10 intermediate its ends and has its other end pivotally connected to one end of a second link 16 which has its other end pivotally connected to the pair of ears 17 on the projection 4 by a pin 18.

The links 15 and 16 are releasing and supporting means for the shoe 5 and its operating mechanism. When it is desired to release the shoe 5, a lifting or upwardly directed force is applied to the links 15 and 16 at their point of connection, which will cause said links to move upwardly into a line position and to force said counter-weighted lever 10 upwardly, thereby releasing the shoe 5. The links 15 and 16 will then preferably be forced slightly beyond their line or center position and will serve to hold said lever 10 in its raised position.

The inner wall of the body 2 is provided with a slightly projected seat portion 20 at a point directly opposite from the clamping shoe 5. The seat 20 is formed concave or curved to fit the curvature of the electrode, and the electrode A, is adapted to be clamped between the seat 20 and shoe 5.

In Figures 3 and 4 I have shown a slightly modified form of electrode holder composed of the continuous ring-like body 2, having the projection 3 on one side and having a slotted projection 30 on the side of the body opposite the projection 3.

The inside wall of the body 2 is recessed at a point opposite the projection 3 to receive a clamping shoe 31. The shoe 31 has its inner face formed concave or curved to fit the curvature of the electrode, and is provided with a stem 32 which extends outwardly through an opening in the body 2 and into the slot in the projection 30.

A crank lever 33, having relatively long and short arms 34 and 35, is fulcrumed on a pivot pin 36 mounted in the slotted projection 30. The short arm 35 of the lever 33 extends downwardly through the slot in the

projection 30 and is loosely mounted in a slot 37 in the stem 32, while the long arm 34 extends away from the body 2 and is provided with a counter-weight 38 which is adjustably locked in position on the arm by a set-screw 39.

The inner wall of the body 2 is provided with a slightly projected seat portion 40 at a point directly opposite from the clamping 10 shoe 31. The seat 40 is formed concave or curved to fit the curvature of the electrode, and the electrode A is adapted to be clamped between the shoe 31 and seat 40.

In operation, the counter-weighted lever 15 mechanism in both constructions will force the clamping shoe against the electrode A and will cause the electrode to be clamped between the integral seat of the holder and the shoe. When the electrode holder becomes 20 heated and expands, the counter-weighted lever mechanism, which applies a constant force to the clamping shoe, will force the shoe against the electrode so as to compensate for the expansion of the holder parts.

25 When it is desired to adjust or remove the electrode, it is only necessary to raise the counter-weighted lever mechanism slightly so as to withdraw the shoe and release the electrode.

30 In Figures 5 and 6 I have shown a still further modified form of electrode holder composed of the continuous ring-like body 2, having the projection 3 on one side and having an opening 45 through the body approximately opposite the projection 3 in which a clamping shoe 46 is slidably mounted. A pair of spaced lugs or ears 47 extend upwardly from the upper edge of the body 2 in line with the side faces of the opening 45, and a second pair 35 of spaced lugs or ears 48 extend outwardly from the side wall of the body in line with the side faces of the opening 45.

40 The shoe 46 has its inner or electrode engaging face serrated so as to bite into and 45 grip the electrode and is adapted to be moved in and out toward and away from the electrode by a toggle link mechanism to be described.

45 The toggle is composed of a link 49 having 50 one end pivotally mounted on a pin 50 adjustably mounted in slotted bearing openings 50^a in the ears 48, and having its other end pivotally connected by a pin 51 to one end 55 of toggle links 52 which have their other ends pivotally mounted on a pin 53, journaled in a bearing lug 54 on the shoe 46.

60 The pin 50 is adapted to be adjusted back and forth in the slotted bearing openings 50^a in the ears 48 so as to vary the throw of the 65 toggle links 49 and 52 and thereby vary the movement of the shoe 46 so as to permit the shoe to grip various sizes of electrodes. Set-screws 65 are provided for locking the pin 50 in its adjusted positions.

65 A tie member or web 66 extends between the

ears 48 and serves to limit the downward movement of the toggle links 49 and 52.

A counter-weight lever 55 is pivotally mounted at one end on a pin 56 journaled in bearing apertures in the ears or lugs 47, and 70 has a counter-weight 57 adjustably secured thereon.

A pair of toggle operating links 58 are pivotally connected at one end to a pin 59 journaled in a bearing in the counter-weight 75 lever 55 and have their other ends pivotally connected to the pin 51 connecting the toggle members.

A counter-weight operating and supporting toggle is composed of pairs of links 60 80 and 61. The links 60 have their upper ends pivotally mounted on a pin 62 journaled in an aperture in the counter-weight lever 55 and have their lower ends pivotally connected to the upper ends of the links 61 by a pin 85 63. The lower ends of the links 61 are pivotally mounted on the reduced ends of the pin 50.

In operation, when it is desired to release the electrode, the toggle composed of links 60 and 61 will be straightened by applying pressure at the point of connection of the links and, as the links 60 and 61 are straightened, the counter-weight lever 55 will be forced upwardly. When the links 60 and 61 are moved into a straight line they will serve 90 as a stiff leg to support or hold the counter-weight lever in elevated or raised position.

95 As the counter-weight lever 55 is raised, it will create a pull on the links 58 so as to 100 collapse the toggle members 49 and 52 and thereby move or pull the shoe 46 away from the electrode.

When it is desired to lock or grip the electrode A, the toggle links 60 and 61 will be 105 collapsed, permitting the counter-weight lever 55 to move down by the weight of the counter-weight 57, which movement will be communicated through the links 58 to the toggle members 49 and 52, so as to extend 110 said members and force the shoe 46 into engagement with the electrode A.

115 While I have shown and described certain specific embodiments of my invention, it will be understood that I do not wish to be limited thereto since various modifications may be made without departing from the scope thereof, as defined in the appended claims.

I claim—

1. An electrode holder for electric furnaces 120 comprising a ring-like continuous body in which the electrode is mounted, a clamping shoe reciprocably mounted in said holder and adapted to be moved toward and away from said electrode, and counter-weighted mechanism for normally forcing said clamping shoe against said electrode.

125 2. An electrode holder for electric furnaces comprising a ring-like continuous body in which the electrode is mounted, a smooth 130

seat portion formed on a portion of the inner wall of said body and contoured to snugly fit the electrode, a clamping shoe mounted in said holder opposite said seat portion, and means for normally forcing said clamping shoe against the electrode.

3. An electrode holder for electric furnaces comprising a ring-like continuous body in which the electrode is mounted, a smooth seat portion formed on a portion of the inner wall of said body and contoured to snugly fit the electrode, a recess in the inner wall of said body opposite said seat, a clamping shoe reciprocably mounted in said recess, and a counter-weighted lever for normally forcing said clamping shoe against said electrode.

4. An electrode holder for electric furnaces comprising a ring-like continuous body in which the electrode is mounted, a smooth seat portion formed on a portion of the inner wall of said body and contoured to snugly fit the electrode, a recess in the inner wall of said body opposite said seat, a clamping shoe reciprocably mounted in said recess, a stem 25 on said shoe, and a counter-weighted operated

toggle mechanism adapted to normally force said clamping shoe against said electrode.

5. An electrode holder for electric furnaces comprising a ring-like body in which the electrode is mounted, a seat formed on a portion of the inner wall of said body and contoured to snugly fit the electrode, a clamping shoe mounted in said holder opposite said seat portion, and a counter-weighted lever mechanism for moving said shoe to clamp 35 said electrode.

6. An electrode holder for electric furnaces comprising a ring-like body in which the electrode is mounted, a seat formed on a portion of the inner wall of said body and contoured to snugly fit the electrode, a recess formed in the inner face of said holder opposite said seat portion, said recess having an inclined rear wall, a wedge-shaped clamping shoe mounted in said recess, and a counter-weighted lever mechanism for moving said shoe vertically to clamp said electrode.

In testimony whereof, I have hereunto set my hand.

EINAR MOLMARK.
